UNITED STATES PATENT OFFICE.

FREDERICK H. FORD, OF MILWAUKEE, WISCONSIN, ASSIGNEE TO THE TOTALUX COMPANY, OF MILWAUKEE, WISCONSIN, A CORPORATION OF WISCONSIN.

HEADLIGHT FRONT OR LENS.

1,302,148.

Specification of Letters Patent. Patented Apr. 29, 1919.

Application filed January 3, 1918. Serial No. 210,329.

To all whom it may concern:

Be it known that I, FREDERICK H. FORD, a citizen of the United States, and resident of Milwaukee, in the county of Milwaukee and State of Wisconsin, have invented new and useful Improvements in Headlight Fronts or Lenses, of which the following is a description, reference being had to the accompanying drawings, which are a part of this specification.

The invention relates to lenses for headlights, such as are commonly used on automobiles and street cars and has for its object to improve the usual plain headlight front by directing the rays of light from the lamp to where they are most needed and where they are not objectionable to an approaching person or vehicle.

The usual form of lamp of the kind mentioned consists of a light source, placed slightly behind the focus of a reflector for what is termed a spread ray and slightly in front of the focus of the reflector for what is termed a cross ray, the reflector being a paraboloid of revolution; the whole mounted in a metal case with a plane glass front. The usual source of light is an incandescent electric lamp having a spiral filament so placed that the axis of the filament is coincident with the axis of the mirror and so held that the position of the lamp is adjustable along this axis. This kind of an arrangement will be assumed in the following explanations though the device hereinafter described may be used in connection with other types of lamp. With either of the adjustments of the light source, using a plane glass front, the road is illuminated directly in front of the vehicle carrying the headlight but not at the sides except at a short distance from the vehicle and the light is spread out ahead of the vehicle at a comparatively short distance. Furthermore that portion of the light which shines above the horizontal plane through the lamp has a blinding effect upon a person on the road looking toward the approaching vehicle.

With these deficiencies of the plane front in mind, I have devised a lens in which the light, which with the plane front produces the objectionable glare, is deflected downwardly and to the sides of the road to light up the adjacent ditch and one in which the light, which with the plane front is thrown ahead, is thrown ahead at a greater distance

and with greater concentration than that of the plane front, it being understood of course that the light thus thrown out forms a lighted field in which portions are more intensified than the remaining part of the field. Thus the lens not only lights up the sides of the road and the ditches adjacent thereto but projects a strong light at a distance ahead of the vehicle, both of which are important factors for safety in driving at night.

The invention further consists in the several features hereinafter set forth.

When the lamp is positioned back of the focus of the reflector to form a spread ray the objectionable glare comes from the upper part of the reflector and when positioned in front of the focus of the reflector for a crossed ray the objectionable glare comes from the lower portion of the reflector.

The following is a description of fronts or lenses designed for use with a spread ray or divergent beam and a crossed ray or beam.

In the drawings:

Figure 1 is a rear view of the device embodying the invention for use with a crossed beam;

Fig. 2 is a sectional view through the lamp equipped with the lens shown in Fig. 1;

Fig. 3 is a section taken on the line 3—3 of Fig. 1;

Fig. 4 is a section taken on the line 4—4 of Fig. 1;

Fig. 5 is a rear view of the device embodying the invention for use with a spread ray;

Fig. 6 is a sectional view through the lamp equipped with the lens shown in Fig. 5;

Fig. 7 is a section taken on the line 7—7 of Fig. 6;

Fig. 8 is a section taken on the line 8—8 of Fig. 6.

Referring to Figs. 1 to 4 inclusive the device for use with a crossed beam consists of a transparent head light front or lens provided with a lower prismatic portion A A' and an upper prismatic portion. The lower prismatic portion A A' comprises two parts having refracting prisms, mutually upwardly inclined in opposite directions and having their bases down, these parts preferably extending a short distance above a horizontal line through the center of the lens. The upper prismatic portion consists of two side prismatic parts B, B' and a central prismatic part C. The two side parts B and

B' each consist of vertically disposed prisms 5, the inclined sides 9 of which slope toward the central part C, the area of the prisms preferably gradually diminishing and their angles increasing from the inner parts of the front toward the outer edges. The central prismatic part C consists of a plane surface 10, a horizontally disposed prism 11 having its inclined side 12 sloping upwardly and away from the inner side of the front, a plane surface 13 and a horizontally disposed prism 14 having its inclined side 15 sloping upwardly and inwardly. A front of this kind is placed over the opening of a parabolic mirror M having a lamp L placed so that the major portion of the filament is behind the center of focus so as to produce what has previously been designated a spread beam. In this construction, the rays from the upper part which are ordinarily reflected upwardly, are by the prismatic parts D and D' reflected downwardly and to the side thus preventing the objectionable glare characteristic of a plane front and at the same time throwing the light to the sides of the road and lighting up the ditches beyond. The two prismatic parts E and E' serve to converge and concentrate the rays of light that are reflected from the lower side parts of the mirror and send these rays out ahead and farther than would be possible with a plane front. The central part C also assists in projecting the rays to a greater distance in front of the vehicle. As is the case with the crossed beam, this arrangement of prisms cooperate to produce a well lighted field in front of the vehicle and to concentrate the light where it is most needed.

In both forms of the drawing the angles of the mutually inclined refracting prisms with respect to the vertical alternately varies, for instance, in each set of prisms the alternate prisms a have angles of fifteen degrees, others a' of ten degrees whereby to produce an overlapping of rays resulting in a clear field though it will be understood that the invention is not confined to this arrangement.

From the foregoing description it will be apparent that both forms of lenses provide for deflecting the light downwardly to prevent the customary disagreeable blinding effect, that the light which ordinarily is reflected upwardly is deflected downwardly and put to useful purpose in lighting the sides of the road and that the light which ordinarily is projected forwardly at a comparatively short distance is concentrated and projected farther ahead of the vehicle, whereby a broad well lighted field is produced.

I am aware that the details of construction herein described are capable of some modification and change and I therefore desire it to be understood that such changes in construction as come within the scope of the appended claims I deem to be within the spirit of my invention.

What I claim as my invention is:

1. A lens for head-lights in which substantially half the front is provided with a plurality of sets of refracting prisms inclined toward each other to refract the light passing through them downwardly and in which the other half of the front is provided

horizontally disposed prism 14' having its inclined side 15' sloping outwardly. A front of this kind is placed over the opening of a parabolic mirror M having a lamp L placed so that the major portion of the filament is behind the center of focus so as to produce what has previously been designated a spread beam. In this construction, the rays from the upper part which are ordinarily reflected upwardly, are by the prismatic parts D and D' reflected downwardly and to the side thus preventing the objectionable glare characteristic of a plane front and at the same time throwing the light to the sides of the road and lighting up the ditches beyond. The two prismatic parts E and E' serve to converge and concentrate the rays of light that are reflected from the lower side parts of the mirror and send these rays out ahead and farther than would be possible with a plane front. The central part C also assists in projecting the rays to a greater distance in front of the vehicle. As is the case with the crossed beam, this arrangement of prisms cooperate to produce a well lighted field in front of the vehicle and to concentrate the light where it is most needed.

In both forms of the drawing the angles of the mutually inclined refracting prisms with respect to the vertical alternately varies, for instance, in each set of prisms the alternate prisms a have angles of fifteen degrees, others a' of ten degrees whereby to produce an overlapping of rays resulting in a clear field though it will be understood that the invention is not confined to this arrangement.

From the foregoing description it will be apparent that both forms of lenses provide for deflecting the light downwardly to prevent the customary disagreeable blinding effect, that the light which ordinarily is reflected upwardly is deflected downwardly and put to useful purpose in lighting the sides of the road and that the light which ordinarily is projected forwardly at a comparatively short distance is concentrated and projected farther ahead of the vehicle, whereby a broad well lighted field is produced.

I am aware that the details of construction herein described are capable of some modification and change and I therefore desire it to be understood that such changes in construction as come within the scope of the appended claims I deem to be within the spirit of my invention.

What I claim as my invention is:

1. A lens for head-lights in which substantially half the front is provided with a plurality of sets of refracting prisms inclined toward each other to refract the light passing through them downwardly and in which the other half of the front is provided

with a central section of horizontally disposed prisms and end sections of vertically disposed prisms.

2. A lens for head-lights in which a part is provided with a plurality of sets of refracting prisms inclined toward each other to refract a part of the light downwardly and in which other parts are provided with vertically disposed prisms to concentrate the 10 light passing through them and project it forwardly.

3. A lens for head-lights in which substantially half the front is provided with a plurality of sets of refracting prisms inclined toward each other to refract the light passing through them downwardly and in which the other half of the front is provided with prisms to project the light, passing 15 through them, forwardly.

20 4. A lens for head-lights in which substantially half the front is provided with a plurality of sets of refracting prisms inclined

toward each other to refract the light passing through them downwardly and in which the side portions of the other half of the 25 front are provided with vertically disposed prisms.

5. A lens for head-lights in which substantially half of the front is provided with horizontally disposed prisms in the central 30 part thereof and vertically disposed prisms bounding both sides of said central part.

6. A lens for head-lights in which substantially half the front is provided with a plurality of sets of prisms to refract the 35 light downwardly and in which the other half of the front is provided with a central horizontally disposed prismatic portion and vertically disposed prisms adjacent said central portion.

In testimony whereof, I affix my signature.

FREDERICK H. FORD.
